UNITED STATES PATENT OFFICE

PAUL GROEBLI, OF NEW YORK, N. Y., ASSIGNOR TO IKLE FRERES & CO. INC., OF NEW YORK, N. Y., A CORPORATION OF NEW YORK

DESIGN FOR AN EMBROIDERED TRIMMING

Application filed January 12, 1932. Serial No. 42,456. Term of patent 3½ years.

To all whom it may concern:

Be it known that I, PAUL GROEBLI, a citizen of the United States of America, and residing in the borough of Manhattan, in the city, county, and State of New York, have invented a new, original, and ornamental Design for Embroidered Trimming, of which the following is a specification, reference being had to the accompanying drawing, forming a part thereof:

The drawing is a view of embroidered trimming showing, between dot and dash lines, my new design.

I claim:

The ornamental design for embroidered trimming as shown and described.

This specification signed this 9th day of January, 1932.

PAUL GROEBLI.
